UNITED STATES PATENT OFFICE.

HENRY FALLER, OF MIDDLE VILLAGE, ASSIGNEE TO JOHN TIMMES, OF BROOKLYN, NEW YORK.

DESIGN FOR A GATE.

SPECIFICATION forming part of Design No. 14,156, dated August 7, 1883.

Application filed April 7, 1883. Term of patent 7 years.

To all whom it may concern:

Be it known that I, HENRY FALLER, a citizen of the United States, residing at Middle Village, in the county of Queens and State of New York, have invented and produced a new and original Design for Gates, of which the following is a specification, reference being had to the accompanying drawing.

This invention relates to an ornamental design for a gate, as illustrated in the accompanying drawing, which represents a face view.

In the drawing, the letters A A' designate the bottom rails, from the outer ends of which rise the posts B B', while from their inner ends rise the meeting-rails C C', respectively. The upper ends of the posts and meeting-rails are united, respectively, by segmental top rails, D D'. Each of the half-gates thus formed is ornamented precisely like the other, and I will proceed to describe the ornaments of one only. On the upper edge of the top rail rest a series of conoidal arabesques, E, of peculiar and ornamental shape. The space between the bottom rail, the post, the top rail, and the meeting-rail is divided by a vertical staff, F, into two open panels, G H. The bottom part of the panel H is occupied by a foil, I, and two curved bars, J, which extend upward above the apex of the foil and diverge, their diverging ends forming the support for arabesques K, from the middle of which extends a stem, L, which supports similar arabesques, K', in an inverted position. The stems of these arabesques are entwined with the stems

of arabesques K', from the center of which rises a stem bearing cross K'', which bears against the top rail, D. The lower portion of the panel G is occupied by two foils, M M', in the interior of each of which are two curved bars, N N N N', respectively, which extend up above the foils and unite into bars N* N'', respectively. The outer arcs of the foils M M' unite at a point, a, forming large foil O, and from the apex of this foil rises a stem, O', which has seven branches, four of which terminate each in an arabesque, O'', of a peculiar scroll shape, while two of said branches bend over each other and over the central branch, b, which carries at its top end a sort of a fleur-de-lis, c. The bars N* N'' extend up to the top rail, and between the upper end of the bar N* and the meeting-rail C is a quarterfoil, d, inclosed between curved stems e e.

What I claim as new, and desire to secure by Letters Patent, is—

The design for a gate, consisting of the bottom rails, A A', posts B B', segmental top rails, D D', vertical staff F, foil I, arabesques K K' K'', cross K'', foils M M O, arabesques O'', stem b, and quarterfoil d, substantially as shown and described.

In testimony whereof I have hereunto set my hand and seal in the presence of two subscribing witnesses.

HENRY FALLER. [L. S.]
